UNITED STATES PATENT OFFICE.

ALBERT HEIMANN, OF NEW YORK, N. Y.

DESIGN FOR A CASING FOR A COMBINED WEIGHING AND ADVERTISING MACHINE.

Application filed April 17, 1924. Serial No. 9,303. Term of patent 14 years.

To all whom it may concern:

Be it known that I, ALBERT HEIMANN, a citizen of the United States, residing in the city of New York, State of New York, have invented a new, original, and ornamental Design for a Casing for a Combined Weighing and Advertising Machine, of which the following is a specification, reference being had to the accompanying drawing, forming a part thereof, wherein—

The drawing is a perspective view of a weighing and advertising machine embodying the design.

What I claim is:

The ornamental design for a casing for a combined weighing and advertising machine, as shown.

ALBERT HEIMANN.
